RIBBON MECHANISM FOR TYPE-WRITING MACHINES.

933,181.

Specification of Letters Patent.

Patented Sept. 7, 1909.

Application filed September 4, 1906. Serial No. 333,216.

To all whom it may concern:

Be it known that I, OSCAR C. KAVLE, a citizen of the United States, residing at Syracuse, in the county of Onondaga and State of New York, have invented a new and useful Improvement in Ribbon Mechanisms for Type-Writing Machines, of which the following is a specification.

This invention relates more particularly to ribbon operating mechanisms for type-writing machines of the visible writing kind in which the ribbon is vibrated to and from the printing position opposite to or over the printing point on the platen so that the writing is exposed to view except when the ribbon is in the printing position, which ordinarily is only momentarily while the type-bars are in motion.

The primary object of the invention is to produce a desirable and efficient mechanism for both feeding and vibrating the ribbon, which will be of comparatively simple, durable and inexpensive construction.

Other objects of the invention may be stated as follows:—to provide two ink ribbons and vibrating mechanism therefor whereby either ribbon can be used or both rendered inactive by the simple movement of a controlling switch or part; to provide a simple power-driven mechanism for feeding the ribbon lengthwise which will be positive and certain in action, simple in construction and require but little power for its operation; to provide simple means for reversing the feed of the ribbon in which successive like movements of the same part will reverse the feed of the ribbon regardless of the direction of movement of the ribbon; to provide means to prevent the tearing of the ribbon from the spools; and to adapt the ribbon vibrating mechanism to machines in which the platen is shifted to print different case characters.

Still another object of the invention is to improve ribbon-operating mechanisms for typewriting machines in the respects herein-after described and set forth in the claims.

In the mechanism forming the subject of this invention two ribbons of different character are employed, enabling the production of different sorts of writing, for instance, they may be of different colors, or one may be a record and the other a copying ribbon. The two ribbons are arranged face to face,

that is, one over or in front of the other, and are attached at their ends to a single pair of spools and simultaneously wound from one spool onto the other in the usual manner of feeding a single ribbon. The ribbons, however, pass through separate vibrating guides, or vibrators, near the printing point and both of these vibrators can be rendered inactive to hold both ribbons out of operative position, so as to expose the printing point and enable the use of the machine for stencil cutting, or either vibrator, at will, can be placed in action to vibrate whichever ribbon it is desired to use, while the other vibrator and ribbon remain inactive below or away from the printing point.

While the mechanism is hereinafter described and shown in the drawings as constructed for feeding and vibrating two ribbons, it is to be noted that either of the devices for feeding the ribbons or for vibrating the ribbons are equally adapted for operating a single ribbon.

In the accompanying drawings, consisting of four sheets: Figure 1 is a fragmentary longitudinal sectional elevation of a front strike typewriting machine provided with ribbon-operating mechanism embodying the invention. Fig. 2 is a plan view, partly in section, line 2—2, Fig. 1, of the ribbon feed mechanism, the operating ratchet wheels for the ribbon spools being partly broken away to disclose the underlying parts. Fig. 3 is a longitudinal sectional elevation of the ribbon feed mechanism in line 3—3, Fig. 2. Fig. 4 is a transverse sectional elevation thereof in line 4—4, Fig. 3. Fig. 5 is a fragmentary section, on an enlarged scale, of the ribbon reversing means. Figs. 6, 7 and 8 are cross sectional elevations thereof in lines 6—6, 7—7 and 8—8, respectively, Fig. 5. Fig. 9 is a detail sectional plan of the clutch for connecting the ribbon spool to its shaft. Fig. 10 is a front elevation, partly in section, in line 10—10, Fig. 1, of the ribbon vibrating mechanism. Figs. 11 and 12 are front elevations of the two ribbon vibrators detached. Fig. 13 is a fragmentary sectional elevation of the vibrating mechanism, on an enlarged scale, in line 13—13, Fig. 10. Figs. 14, 15 and 16 are horizontal sectional plans thereof in lines 14—14, 15—15 and 16—16, respectively, Fig. 13. Fig. 17 is a sectional plan of the ribbon

vibrators and their controlling switch lever, showing the latter in a different position from that which it occupies in Fig. 16.

Like letters of reference refer to like parts in the several figures.

A represents the frame of a typewriting machine, *a* the top plate thereof, B the platen, C the usual horizontally traveling carriage on which the platen is journaled, *c* the usual spring-actuated drum connected to the carriage by means not shown, for causing the horizontal travel thereof, D the finger key levers for actuating the type-bars, one of which with its connections to the key lever is shown by dotted lines at E in Fig. 1. These parts may be of any usual or suitable construction, but the top plate *a* is preferably secured to the main frame in any suitable manner enabling it to be detached with the parts carried thereby.

The machine illustrated is of that kind in which the type-bars carry two sets of type, and the platen is normally in printing relation to the lower case type and is shifted into printing relation to the upper case type, and the carriage for this purpose travels in guides *f* on a shift frame F which is pivoted at *f'* to the rear portion of the top of the main frame to oscillate vertically. The shift frame does not partake in the horizontal travel of the carriage but is simply capable of swinging up and down to shift the carriage and platen. It can thus be raised and lowered by any suitable means, such, for instance, as a pitman *f''*, Fig. 1, connecting a slotted front extension *f³* of the shift frame with a crank disk *f⁴* which is oscillated by a gear pinion *f⁵* thereon meshing with a toothed segment *f⁶* secured to a rock shaft *f⁷* provided at opposite ends with rock arms actuated by rocking shift levers at opposite sides of the machine. One shift lever and one rock arm are shown at *f⁸* and *f⁹*, respectively, Fig. 1. This mechanism for shifting the carriage is fully described in the application of E. G. Latta for typewriting machines, filed June 14, 1905, No. 265,217, and a further description thereof herein is unnecessary.

G G represent the two ink ribbons, which, as before stated, are arranged face to face or one in front of the other, and are attached at opposite ends to a pair of spools H H' which are preferably arranged above the top plate *a* of the frame at opposite sides of the front portion thereof on upright shafts *h* *h'* journaled in suitable bearings *h²* on the top plate. These spools are operated by feed mechanism to be hereinafter described, to wind the ribbons simultaneously onto one spool from the other in the same manner as if a single ribbon connecting the spools were employed. The ribbons pass through stationary guides *i* of suitable construction, one of which is shown in Fig. 1, located ad-

jacent to the spools, and through separate vibrating guides, or vibrators K K', Figs. 1 and 10-15, arranged vertically one in front of the other adjacent to the printing point of the platen. These vibrators are arranged to normally hold the ribbons down below the printing point so as to expose the writing, and means are provided for reciprocating either vibrator independently of the other to vibrate whichever ribbon it is desired to use to and from printing position between the printing point of the platen and the type-bars. Each vibrator, see Figs. 11 and 12, preferably consists of a piece of sheet metal having a flat body portion with side wings 80 or parts at its upper end bent to form open guide loops *k* for the ribbon extending forwardly at an angle from the body portion toward the ribbon spools and separated by an intervening slot or opening which allows 85 the type to strike the ribbon. The guide loops of the rear vibrator are spaced farther apart than those of the front vibrator so that the two vibrators can be arranged close together, one in front of the other, as shown 90 in Fig. 15, and one reciprocated without interference with the other. Each vibrator has at one side a depending leg provided at its lower end with a lateral projection or foot *k'*. These feet project laterally toward 95 each other but are separated by an intervening space, and the leg of the front vibrator is preferably bent rearwardly somewhat to place both feet in line opposite to each other, see Figs. 13, 16 and 17. The vibrators are 100 arranged to slide vertically in guide grooves or ways *l*, Fig. 14, in a suitable upright support or bracket *l'*, Figs. 1, 10 and 13-15, having rearwardly projecting arms secured by rivets *l²* or otherwise in the slotted front 105 extension *f³* of the shift frame. The bracket *l'* and vibrators are located in front of the scale bar *l³* of the carriage and are preferably provided with registering openings through which the scale bar can be seen. 110 The opening of the bracket has beveled edges, and a cross wire *l⁴*, Fig. 10, is preferably provided in the opening which contrasts in color with the scale bar and serves as a center index or printing point indicator. The vibrators could be constructed and mounted on the shift frame in any other suitable manner.

M, Figs. 1, 10, 13, 16 and 17, represents a lever pivoted in the slotted front extension *f³* of the shift frame and having a horizontally projecting arm with a hooked end which extends between the legs of the two vibrators and bears on the two feet thereof. A switch lever or spring *m* is pivoted at its rear end in a slot in the vibrator lever M and extends horizontally beneath the hooked arm thereof, having its free end bent to form a loop or handle by which it can be swung on its pivot to place it beneath the foot of 130

either vibrator, or in a central position between the vibrator feet. The switch is narrower than the distance between the vibrator feet, and when placed centrally it will pass upwardly between the feet when the vibrator lever is oscillated without lifting either vibrator, whereas if it is shifted laterally to one side beneath the foot of either vibrator, that vibrator will be lifted 10 when the lever is oscillated, while the other vibrator will remain stationary. Thus by changing the position of the switch both vibrators can be rendered inactive or either one desired can be put in operation. The 15 vibrator lever will hold both vibrators down when at rest in its lower position, and will always draw down either vibrator which might be raised, but it will not lift either vibrator when the switch spring is placed 20 centrally. The switch lever can be held from accidental movement by frictional contact with the vibrator lever, or in any other convenient manner.

The vibrator lever is operated in the 25 machine illustrated by the following means, see Figs. 1, 2 and 10: The lever has a depending arm connected by a link n to an arm n' secured to and projecting upwardly from the central portion of a horizontal rock shaft n^2 journaled at its ends in suitable 30 bearings in the sides of the frame A. The rock shaft has forwardly projecting rock arms n^3 , Fig. 2, near its ends from which is pivotally suspended a universal bar N arranged horizontally below the key levers. 35 The universal bar is engaged and depressed by each key lever that is moved to operate a type-bar, and oscillates the vibrator lever through the described connections. Unless 40 the vibrator switch is in a central position one of the vibrators will thus be raised and the ribbon carried thereby placed in position to be struck by the type-bar to make an impression whenever a type-bar is actuated, and 45 the vibrator will again lower the ribbon to expose the writing when the key lever is released and the type-bar returned. A spring n^4 is connected to the universal bar at any suitable point for restoring the same and 50 the other parts of the vibrating mechanism to the normal position. The universal bar N has no connection whatever with the carriage escapement and a separate and distinct universal bar N', Fig. 1, is employed for 55 operating the escapement which is indicated at N'. This second universal bar is preferably of that sort arranged near the type-bar segment to be operated by the type-bars when near the limit of their excursions to 60 the platen. Actuators N⁵ are shown in Fig. 1 for transmitting motion from the type-bars to the universal bar N' for rocking it to operate the escapement. This escapement actuating mechanism thus briefly referred 65 to and shown in Fig. 1 forms no part of the

present invention but is fully disclosed in my prior application, Serial No. 320,541, filed June 7, 1906. The universal bar N for the vibrators is preferably located somewhat below the lower edges of the key levers, as 70 shown in Fig. 1, so that the key levers can be depressed far enough to start the type-bar actions before the universal bar is engaged and moved to operate the vibrator. The type-bars are preferably operated with an 75 accelerating motion, but the ribbon vibrator has a uniform motion which enables the ribbon to reach the printing position at the proper time without danger of the vibrator slipping up on the ribbon, and the wear in 80 the vibrating mechanism is lessened, and the mechanism is preferably so timed that the carriage escapement is not operated until after the ribbon reaches the printing position. As the vibrators and their operating 85 lever are mounted on the shift frame F they are shifted with the platen and their relation to the platen remains the same, but the universal bar N and rock shaft n^2 are supported by the main frame. Therefore, to insure 90 practically equal movements of the vibrators in both positions of the shift frame, the vibrating mechanism is so proportioned and arranged that the link n will occupy the full line position, shown in Fig. 1, below a line 95 passing through the pivot joining the link to the rock arm n' and the pivotal axis of the shift when the shift frame is in its lower position, and will cross said line to the position shown by broken lines in said Fig. 1 100 when the shift frame is raised. By this arrangement of the link n the movements thereof by the rock arm will be substantially similar in both positions of the link and consequently substantially equal movements of 105 the vibrators will be produced in both positions of the shift frame. This same vibrating mechanism could be used for operating a single vibrator for one ribbon. The arrangement and construction of the two vibrators and the means for actuating them in the manner described, whereby either of 110 two ribbons can be used or both allowed to remain inactive out of the path of the type, could, however, be varied without departing 115 from the invention.

The mechanism for operating the ribbon spools to feed the ribbons lengthwise is preferably constructed as follows: O, Figs. 1, 3 and 4, represents a gear pinion which is 120 secured to the carriage-driving spring drum and meshes with a toothed rack P which is movable crosswise of the machine in a guide slot p in the frame top plate a . The rack bar has a depending part p' provided 125 with a socket or opening seated on a reduced cylindrical part q of a horizontal feed bar Q which is arranged below the top plate a and is reciprocated with the rack bar. The feed bar has a cylindrical portion at one 130

end supported in a bearing q' , Fig. 4, depending from the top plate a in which the bar is adapted to slide and turn, and the other end of the bar passes through a bearing sleeve q^2 , Figs. 4-8, arranged to turn in a bearing q^3 depending from the top plate. The sleeve preferably has a reduced portion seated in the bearing whereby it is held from longitudinal movement, and has a hole of 10 cross-shape in cross section in which a correspondingly shaped end portion of the feed bar engages, whereby the bar can slide in the sleeve but will be turned by turning the sleeve. The feed bar has another cross-shaped portion near its opposite end and two opposite edges of each cross-shaped portion are smooth and the other two opposite edges have teeth q^4 with inclined and abrupt faces. The abrupt faces of the 15 teeth at both ends of the rod face in the same direction, but the teeth at one end of the rod are disposed in a plane at right angles with respect to the teeth at the other end of the rod, that is, the teeth at one end 20 of the rod will extend horizontally therefrom while the teeth at the other end of the rod extend vertically. By turning the rod successive quarter revolutions, first one toothed edge at one end of the rod and then 25 one toothed edge at the other end of the rod will be placed downward, which is the operative position. A flat spring q^5 , Figs. 5 and 6, secured at one end of the underside 30 of the top plate and bearing at its free end against a rectangular part q^6 of the sleeve serves to hold the sleeve and rod stationary but allows it to be turned by the application of a little force.

R R', Figs. 1-3, represent two ribbon feed 40 levers which are pivoted beneath the top plate a at opposite sides of the machine in any suitable manner, preferably on shouldered screws r depending from the top plate. The rear ends of the levers extend beneath 45 and are held yieldingly up by their resilience against the cross-shaped parts at the opposite ends of the feed bar and have upwardly directed teeth or edges r' for engagement with the teeth on the feed bar. 50 The other ends of the levers are provided with toothed segments r^2 r^3 meshing with toothed segments on pawl levers S S' journaled to oscillate on the lower ends of the spool shafts h h' respectively. The pawl levers have pawls s pivoted thereto which coöperate with ratchet wheels s' secured to the spool shafts to turn the spools. The free ends of the pawls are pressed toward the ratchet wheels, for instance, by springs s^2 55 connecting the pawls to the pawl levers, and the heels of the pawls are adapted to strike fixed stops, such as pins s^3 depending from the top plate a , to limit the return movements of the pawl levers and swing the free 60 ends of the pawls out of engagement with

the teeth of the ratchet wheels. The pawl levers are oppositely arranged and the segment r^2 of one of the feed levers R extends in front of its spool shaft and is internally toothed while the other segment is located 70 in rear of its spool shaft and is externally toothed, whereby the movements of the rear ends of the feed levers in the same direction will turn the spools in opposite directions. Suitable return springs s^4 are provided for 75 moving the feed levers in the direction opposite to that in which they are moved by the feed bar.

The feed bar is reciprocated with the platen carriage by the toothed rack and pinion, and when it is in the position shown in Figs. 2 and 4 one of the toothed edges at its left-hand end will be in engagement with the left-hand feed lever which will reciprocate with the feed bar so that the 80 ratchet and pawl actuated thereby will slowly turn the left-hand spool upon each travel of the carriage to the left in writing a line, and the pawl will ride backwardly over the ratchet wheel to take a new hold each time 85 the carriage is set back. The rear end of the other feed lever R', however, will bear against one of the smooth edges at the right-hand end of the feed bar and will not be reciprocated thereby but will be held by its 90 spring s^4 in the position shown in Fig. 2, with its pawl against the back-stop s^3 and out of engagement with the ratchet wheel 95 for the right-hand spool so as not to interfere with the backward rotation of this 100 spool. The ribbons will thus be wound onto the left-hand spool from the other one, or fed in one direction as long as the feed bar Q remains in the position shown. When it 105 is desired to reverse the feed of the ribbons, the feed bar is turned one quarter of a revolution, which turns one of the toothed edges at its right-hand end down into engagement with the right-hand feed lever R' whereby 110 this lever will be brought into action while the other feed lever will bear against one of the smooth edges at the left-hand end of the feed rod and will be retracted by its spring 115 s^4 to the position shown in Fig. 2, with the pawl actuated thereby against its stop and out of engagement with its ratchet wheel. When the feed bar is now reciprocated with the carriage the left-hand feed lever will remain inactive and the ribbon will be fed in the opposite direction by the right-hand feed 120 lever. One feed lever is thus always inactive with the pawl actuated thereby against its stop and out of engagement with its ratchet wheel so as not to interfere with the unwinding of the ribbons from the spool 125 operated thereby, but the lever which is in operation will only assume this position when the carriage is set back to the full limit of its travel, which will not occur when the left-hand margin stop is set for paragraph- 130

ing or for producing the usual margin at the left-hand edge of the sheet, and the pawl which is in action will ordinarily, therefore, be in operative engagement with its ratchet 5 wheel ready to turn the spool upon any movement of the carriage to the left. By providing a number of teeth on each toothed edge of the feed bar, the latter can be turned in any position of the carriage and one feed 10 lever will always be engaged by one of the teeth on the bar. If the ribbon is reversed when the carriage is at the left, the feed lever which is thrown into action will simply overrun the teeth of the feed bar when the 15 carriage is set back to the right, and if the feed bar is turned in an intermediate position of the carriage one feed lever will intercept the nearest tooth on the feed bar and will be driven thereby until the carriage is 20 set back, when the lever will overrun the teeth and assume the proper position for the next line.

A friction washer T of any suitable kind preferably surrounds each spool shaft between its bearing and the ratchet wheel to prevent the spools from turning too freely and allowing the ribbons to unwind from one spool faster than they are wound upon the other.

30 In the feed mechanism described, each spool has independently operated driving devices and it is impossible for both spools to be driven at the same time. The mechanism is simple, and occupies but little space under 35 the top plate of the frame by which it is protected from dirt and injury, and it can be readily assembled on the removable top plate or removed therewith from the machine for repairing. It eliminates the usual expensive 40 train of bevel gearing. The feed mechanism could be used for a single ribbon without change except that smaller spools could be employed. This same mechanism could also be used in connection with vibrating means 45 different from those described. Different means could also be used for transmitting the movements of feed levers actuated by a reciprocating feed rod in the manner described to the ribbon spools, and the construction 50 of the feed bar and manner of mounting the same and the means for reciprocating the bar could also differ without departing from the invention.

The feed bar is turned, as explained, for 55 reversing the ribbon feed preferably by the following means: U, Figs. 1-3, represents a push rod arranged horizontally at one side of the machine to slide in suitable bearings on the frame A and having a push button u 60 at its front end by which it can be pushed rearwardly. The rod has a flexible rear extension adapted to engage a ratchet wheel u' having four teeth formed on or secured to the bearing sleeve q^2 for the feed bar. The 65 push rod is held in a forward position and

returned to this position after actuation by a suitable spring u^2 , Figs. 1-3, secured to the front of the frame A and bearing against the rear end of the push button. Each time the push rod is pushed rearwardly its rear 70 end will engage the ratchet wheel u' and turn the bearing sleeve q^2 and feed bar one quarter of a revolution, and by reason of the described construction and arrangement of the feed bar and feed levers a different 75 lever will be thrown into action and the ribbon fed in a different direction each time the push rod is pushed rearwardly. The ribbon is therefore reversed, no matter which way it has been feeding, by a rearward or 80 like movement of the push rod and the operator does not have to ascertain the direction of movement of the ribbons, or the position of any of the parts to reverse the feed. Any other suitable device for turning the feed bar to reverse the feed could 85 be employed.

In order to prevent the tearing of the ribbons from the spools, each spool is preferably releasably coupled to its shaft so that the shaft can turn independently of the spool in case that the operation of the machine and feed mechanism is continued after the ribbon is completely unwound from the spool. The coupling shown, see Figs. 1-3-9, 90 consists of a collar V having flat sides surrounding and adapted to turn on an enlargement v on the spool shaft, also having flat sides, and a U-shaped spring v' which embraces the collar and bears against the 100 flat faces of the enlargement. The collar has a pin v^2 which enters a hole in the spool to turn the spool. The spring v' will cause the collar and spool to turn with the shaft unless an undue strain is placed upon the 105 ribbon and spool, when the spring will yield and allow the shaft to turn in the collar without turning the latter and the spool.

I claim as my invention:

1. In a typewriting machine, the combination of a universal bar controlling the carriage escapement, and a ribbon vibrating mechanism independent of said universal bar and constructed to move the ribbon to the printing position with a substantially 110 uniform motion in advance of the operation of said universal bar, substantially as set forth.

2. In a typewriting machine, the combination of a universal bar controlling the carriage escapement, and ribbon vibrating mechanism including a second universal bar which is actuated to place the ribbon in printing position in advance of the actuation of said universal bar for the carriage escapement, substantially as set forth. 120

3. In a typewriting machine, the combination of type-bars, key levers therefor, a carriage escapement, a universal bar for the carriage escapement actuated by the im- 130

pacts of the type-bars, and a ribbon vibrating mechanism which is independent of said universal bar for the carriage escapement and is actuated by the key levers for 5 vibrating the ribbon with a substantially uniform movement, substantially as set forth.

4. In a typewriting machine, the combination of a pivoted shift frame supporting the platen, a ribbon vibrator supported by said 10 shift frame and movable therewith to maintain substantially the same relation to the platen in different positions of the shift frame, an actuating rock arm for the vibrator having a fixed pivotal support, a link 15 connected at one end to said rock arm, and a lever pivoted on the shift frame and connected to the other end of said link and to the vibrator, said link being movable when the shift frame is oscillated across a line 20 passing through the pivotal axis of the shift frame and the joint connecting said link and rock arm whereby substantially like movements of the vibrator are produced in different positions of the shift frame, substantially 25 as set forth.

5. In a typewriting machine, the combination of a platen which is shifted for printing different case characters, an upright bracket which is shifted with the platen, a 30 ribbon vibrator slidably supported on said bracket, and means for sliding the vibrator substantially equal distances on the bracket in different positions thereof, substantially as set forth.

35 6. In a typewriting machine, the combination of a movable shift frame supporting the platen, a ribbon vibrator supported by said shift frame and movable therewith to maintain substantially the same relation to the 40 platen in different positions of the shift frame, said vibrator being movable vertically toward and from printing position, a lever pivoted to said shift frame and connected to the vibrator, and mechanism for actuating 45 said lever, substantially as set forth.

7. In a typewriting machine, the combination of a shift frame pivoted at its rear to oscillate vertically, a platen supporting carriage which travels laterally on said shift 50 frame, a rigid bracket at the front central portion of said shift frame, a ribbon vibrator movable on said bracket, a lever pivoted on said shift frame and connected to the vibrator, and means for vibrating said lever in 55 either position of the shift frame, substantially as set forth.

60 8. In a typewriting machine, the combination of a plurality of ribbons, a vibratory guide for each ribbon, a common actuating device for said guides, means for causing said actuating device to vibrate any one of said guides separately toward and from the printing position, and means independent of said actuating device for movably supporting said guides, substantially as set forth.

9. In a typewriting machine, the combination of two ribbons, independently movable vibrators for said ribbons, and means for actuating one of said vibrators which normally holds both ribbons out of printing 70 position, substantially as set forth.

10. In a typewriting machine, the combination of two ribbons arranged one in front of the other adjacent to the printing point, independently movable vibrators for 75 the ribbons, means for movably supporting said vibrators and retaining them vertical, and an operating device independent of said supporting means which is separately connectible to said vibrators, substantially as 80 set forth.

11. In a typewriting machine, the combination of a pair of spools, two ribbons attached to said spools, and two ribbon vibrators arranged one in front of the other 85 and having guide wings directed toward said spools, the wings of one vibrator being spaced farther apart than those of the other vibrator, substantially as set forth.

12. In a typewriting machine, the combination of two ribbons, two vibrators for 90 said ribbons arranged to reciprocate one in front of the other and having opposite spaced projections, a lever bearing on said projections to move said vibrators in one direction, 95 and a part on said lever movable to a position between said projections or opposite to either projection for moving one of said vibrators in the opposite direction, substantially 100 as set forth.

13. In a typewriting machine, the combination with a carriage and driving means therefor, of a bar which is reciprocated by said driving means, ribbon spools, pivoted levers operatively connected to said spools 105 for transmitting motion thereto from said reciprocating bar, and means for operatively connecting one of said levers to said reciprocating bar, substantially as set forth.

14. In a typewriting machine, the combination with a carriage and driving means 110 therefor, of a bar which is reciprocated by said driving means, ribbon spools, pivoted levers operatively connected to said reciprocating bar, and ratchet and pawl mechanism 115 between said levers and spools, substantially as set forth.

15. In a typewriting machine, the combination with a carriage and driving means therefor, of a gear wheel driven by said carriage driving means, a rack bar reciprocated by said gear wheel, ribbon spools, and pivoted levers operatively connected to said spools for transmitting motion thereto from said rack bar, and means for operatively 120 connecting one of said levers to said rack bar, substantially as set forth.

16. In a typewriting machine, the combination with a carriage and driving means therefor, of a bar which is reciprocated by 125

said driving means, ribbon spools, pivoted levers operatively connected to said spools for transmitting motion thereto from said reciprocating bar, and means for connecting 5 one lever to said bar and disconnecting the other lever therefrom whereby said levers are actuated separately, substantially as set forth.

17. In a typewriting machine, the combination with a carriage and driving means therefor, of a bar which is reciprocated by said driving means, ribbon spools, pivoted levers operatively connected to said spools to rotate said spools in opposite directions 10 by movements of the levers in the same directions, and means for operatively connecting one of said levers to said reciprocating bar, substantially as set forth.

18. In a typewriting machine, the combination with a carriage and driving means therefor, of a bar which is reciprocated by said driving means, ribbon spools, pivoted levers operatively connected to said spools to rotate said spools in opposite directions 20 by movements of the levers in the same direction, and means for operatively connecting said levers separately to said reciprocating bar whereby like movements of the bar will produce opposite rotations of said 25 spools, substantially as set forth.

19. In a typewriting machine, the combination of ribbon spools, pivoted levers operatively connected to said spools for rotating the same, an adjustable reciprocating bar 35 constructed to operatively engage one of said levers in one position of the bar to drive one spool and in another position of the bar to operatively engage the other lever to drive the other spool, substantially as set forth.

40 20. In a typewriting machine, the combination of ribbon spools, pivoted levers operatively connected to said spools for rotating the same, an adjustable reciprocating bar adapted in one position thereof to operatively engage one of said levers to drive one 45 spool and release the other lever and spool, and in another position to release the first lever and spool and operatively engage the other lever to drive the other spool, substantially as set forth.

50 21. In a typewriting machine, the combination with a carriage and driving means therefor, of ribbon spools, a bar which is reciprocated by said driving means, centrally pivoted levers each operatively connected at one end to one of said spools for transmitting motion thereto from said bar, and means for operatively connecting the opposite end of one of said levers to and disconnecting the opposite end of the other lever from said bar, substantially as set forth.

55 22. In a typewriting machine, the combination of ribbon spools, centrally pivoted feed levers one having an externally and the other an internally toothed segment, pawl le-

vers connected to said spools and having gear segments meshing with the toothed segments of said feed levers, a reciprocating bar, and means for operatively connecting said feed levers alternately to said bar, substantially as set forth. 70

23. In a typewriting machine, the combination of ribbon spools, pivoted levers operatively connected to said spools, a reciprocating bar having teeth for engagement with 75 said levers, and means for engaging one lever with the teeth on said bar and disengaging the other lever from said teeth, substantially as set forth.

24. In a typewriting machine, the combination of ribbon spools, pivoted levers operatively connected to said spools, a reciprocating rotatably adjustable bar provided with means for engagement with said levers, means for turning said bar to different positions for engagement first with one of said levers and then with the other, and means for releasably holding said bar in different positions, substantially as set forth. 80

25. In a typewriting machine, the combination with a carriage, and driving means therefor, of ribbon spools, pivoted levers operatively connected to said spools, a bar reciprocated by said carriage driving means, a rotatable feed bar connected to said reciprocating bar and having teeth and smooth edges for engagement with said levers, the teeth being arranged to engage one lever in one position of the bar and the other lever in the other position of the bar, and means 90 for rotatably adjusting said feed bar, substantially as set forth. 95

26. In a typewriting machine, the combination of ribbon feeding means, and reversing means therefor, including a push-rod 105 which is moved in the same direction to reverse the ribbon feed regardless of the direction of movement of the ribbon, substantially as set forth.

27. In a typewriting machine, the combination of ribbon feeding means, and reversing means therefor including a push-rod which has an endwise movement only and reverses the ribbon feed upon successive movements thereof in the same direction regardless of the direction of movement of the ribbon, substantially as set forth. 110

28. In a typewriting machine, the combination of ribbon spools, a feed rod and connections for rotating said spools, said rod 120 being rotatably adjustable for reversing the movement of the ribbon feed, and a push-rod for turning said feed rod, substantially as set forth.

29. In a typewriting machine, the combination of a main frame which supports the type-bar action and is provided with a removable top plate, a ribbon, and mechanism for feeding said ribbon which is supported wholly by said top plate and is removable 125 130

therewith from the main frame, substantially as set forth.

36. The combination of a ribbon, ribbon spools, means for driving the same, and connections between the spools and driving means for releasing the spools therefrom under abnormal strain on the ribbon to prevent tearing the ribbon, substantially as set forth.

10 31. The combination of a ribbon spool, a spool shaft, a collar journaled on said shaft and connected to said spool, a spring which is connected to said collar and bears against a flat face on said shaft to cause the collar to 15 turn with said shaft except when subject to abnormal strain, substantially as set forth.

32. In a typewriting machine, the combination of ribbon spools located at the front portion of the machine, horizontally swinging levers arranged at opposite sides of the machine, operative connections between said levers and said spools, and means at the rear portion of the machine for operating said levers to drive one or the other of said spools, 25 substantially as set forth.

33. In a typewriting machine, the combination of ribbon spools located at the front

portion of the machine, levers at opposite sides of the upper portion of the machine which extend rearwardly from said spools, 30 operative connections between said levers and said spools, and power-actuated means at the rear portion of the machine for operating said levers to drive one or the other of said spools, substantially as set forth. 35

34. In a typewriting machine, the combination with a platen carriage and its driving means, of ribbon spools located at the upper front portion of the machine, horizontally swinging levers arranged at opposite sides of the machine beneath the top plate thereof, operative connections between said levers and said spools, and means at the rear portion of the machine actuated by said carriage-driving means for operating said levers to drive one or the other of said spools, 40 45 substantially as set forth.

Witness my hand, this 30th day of August, 1906.

OSCAR C. KAVLE.
